(57) **CLAIM**

The ornamental design for a display screen with icon, as shown and described.

DESCRIPTION

FIG. 1 is a front view of a first embodiment of a display screen with icon showing the new design; and,

FIG. 2 is a front view of a second embodiment of a display screen with icon.

The broken line showing of the remainder of the icon and display screen is for environmental purposes only and forms no part of the claimed design. The difference in shading in the figures indicates a contrast of appearance and does not depict any particular color, texture or material.
